INTERNAL COMBUSTION ENGINE

Ricardo D. Cayabyab, Delano, Calif.

Application July 7, 1936, Serial No. 89,392

2 Claims. (Cl. 123—53)

This invention relates to internal combustion engines of the four cycle type and has for the primary object the provision of a device of this character which may be successfully operated at increased compression ratios than heretofore possible and without the danger of pre-ignition and eliminates the use of electrical and similar ignition systems or injectors now employed in engines of the Diesel type.

Another object of this invention is the provision of an engine of the above stated character having means whereby fuel and purified exhaust gases may be compressed separately from air and the compressed air, fuel and exhaust gases allowed to commingle at the beginning of the proper cycle of the engine to bring about igniting and the expansion thereof for action on the pistons of the engine employed for separately compressing the fuel and exhaust gases and the air.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation, partly in section, illustrating an internal combustion engine constructed in accordance with my invention.

Figure 2 is a vertical sectional view illustrating the engine.

Figure 3 is a horizontal sectional view taken on the line 3—3 of Figure 2.

Figure 4 is a horizontal sectional view taken on the line 4—4 of Figure 2.

Figure 5 is a fragmentary end elevation showing the connection between the valves of the engine with the end cover of the engine removed.

Figure 6 is a diagrammatical view showing the arrangement of the air and fuel compression chambers and the relation of certain valves thereto.

Figure 7 is a sectional view taken on the line 7—7 of Figure 2, showing the arrangement of the valves during the suction stroke of the piston.

Figure 8 is a sectional view taken on the line 8—8 of Figure 2 showing the valves positioned on the power stroke of the piston.

Figure 9 is a sectional view taken on the line 9—9 of Figure 2 showing the position of the valves on the exhaust stroke of the piston.

Figure 10 is a fragmentary sectional view taken on the line 10—10 of Figure 2 showing the posi-

tion of the valves on the compression stroke of the piston.

Figure 11 is a transverse sectional view drawn on an enlarged scale showing one of the valves and illustrating intake and exhaust passages 5 thereto.

Referring in detail to the drawings, the numeral 1 indicates a cylinder block of the engine and 2 a base. The cylinder block has formed therein cylinders 3 and 4 in which reciprocate 10 pistons 5 and 6. Said pistons are connected to a common crank 7 by connecting rods 8. The crank 7 forms part of a crank shaft 9 journaled in the base 2. The cylinder 3 is employed for compressing fuel while the cylinder 4 is employed 15 for compressing air, that is, during one cycle of operation of the engine and which will be hereinafter more fully described. The block 1 includes a cylinder head 10 to form a closure for the cylinders 3 and 4. Communicating water 20 cooling jackets 11 are provided for the cylinder head and the cylinder block. The pistons being connected to a common crank move together on each cycle of operation of the engine.

The cylinder head has formed therein intake 25 chambers 12 and 13, also has formed therein exhaust passages 14 and 15. Connected to the intake chamber 12 is a fuel intake manifold 16 to which is connected a carbureter 17. An exhaust manifold 18 is connected to the exhaust chambers 30 14 and 15 and is also connected to a gas purifier 19 of any conventional construction. A gas cooler 20 is connected to the gas purifier 19 and to the air intake of the carbureter 17. The gas cooler is of any conventional construction. The 35 gas purifier 19 has ports 21 opening to the atmosphere for the purpose of allowing undesirable exhaust gases to escape to the atmosphere while desirable exhaust gases pass to the gas cooler 20 and thence to the carbureter 17 for 40 mixing with the fuel received through a supply pipe 22. Any type of fuel may be employed, preferably a low grade of petroleum product. An air manifold 23 is connected to the intake chamber 13 and has connected thereto an air filter 45 24 of any conventional construction.

Formed in the cylinder head 10 are fuel compression chambers 26, 27, and 28. The fuel compression chamber 28 is connected to the fuel compression chambers 26 and 27 by passages 29. 50 The fuel compression chambers 26 and 27 are arranged in superimposed relation above the cylinder 4, while the fuel compression chamber 28 is located above the cylinder 3. Formed in the cylinder head 10 are air compression chambers 39, 55

31, and 32. The air compression chamber 30 is connected to the air compression chambers 31 and 32 by passages 33. The fuel compression chamber 27 is connected to the cylinder 3 by 5 passages 34. The air compression chamber 32 is connected to the cylinder 4 by a passage 35. The fuel compression chambers are always in communication with the cylinder 3, while the air compression chambers are always in communication 10 with the cylinder 4.

The fuel compression chamber 27 is in communication with the cylinder 4 by intake and exhaust ports 36 and 37. The compression chambers 27, 30 and 26 are in communication by intake 15 and exhaust ports 38 and 39. The fuel compression chamber 26 is in communication with the intake and exhaust chambers 12 and 14 by intake and exhaust ports 40 and 41. The air compression chamber 32 is in communication with 20 the cylinder 3 by intake and exhaust ports 42 and 43. The compression chambers 32, 28 and 31 are in communication by intake and exhaust ports 44 and 45. The air compression chamber 31 is in communication with the intake and exhaust 25 passages 13 and 15 by ports 46 and 47.

Rotary valves 48 open and close the communication between compression chambers 26, 30, 27 and the cylinder 4. The valves 48 have intake and exhaust ports or passages 49 and 50. Rotary 30 valves 51 similar to the valves 48 control the communication between the chambers 31, 28, 32 and the cylinder 3 and said valves 51 have intake and exhaust passages or ports 52 and 53.

Rotary valves 54 control communication between the fuel compression chamber 26 and the intake and exhaust chambers 12 and 14. The valves 54 are provided with intake and exhaust ports or passages 55 and 56. Rotary valves 57 control the communication between the air compression chamber 31 to the exhaust and intake chambers 15 and 13 and are provided with exhaust and intake ports or passages 58 and 59. The valves 48 and 54 are geared together by a series of intermeshing gears 60. The valves 51 and 57 are geared together by a series of intermeshing gears 61. One of the valves 48 has secured thereto a gear 62 meshing with an idler gear 63 suitably journaled to the cylinder block and connected to the crank shaft by a gear 64. One of the valves 51 has secured thereto a gear 65 meshing with an idler gear 66 suitably journaled to the cylinder block and is connected to the crank shaft 9 by a gear 67. Casings 68 are secured to the cylinder block and cylinder head 50 for enclosing the gears 62 to 67, inclusive, also for enclosing the intermeshing gears 60 and 61. Thus it will be seen that all of the valves are driven from the crank shaft 9.

The intake and exhaust ports 49 and 50 of the valves 48 parallel each other. Also the intake and exhaust ports 52 and 53 of the valves 51 parallel each other. The valves 54 and 57 have the intake ports thereof arranged angularly to the exhaust ports thereof. A clearer illustration of the arrangement of the intake and exhaust ports relative to each other in the valves 54 and 57 is clearly shown in Figure 11, also in Figures 7 to 10, inclusive. Figures 7 to 10, inclusive, clearly illustrate the grouping of the valves 48, 54, 51 and 57 and further show the direction of rotation of the various valves by the arrows.

During the working or power stroke and also the exhaust stroke of the piston of the cylinder 4 the valves 48 place the chambers 26, 30 and 27 directly in communication with said cylinder 4.

During the working or power stroke and also the exhaust stroke of the piston of the cylinder 3 the valves 51 place the compression chambers 31, 28 and 32 in communication with said cylinder 3. During the exhaust strokes of the pistons of the cylinders 3 and 4 the valves 51, 57, 48 and 54 place said cylinders in direct communication with the intake and exhaust chambers 13, 12, 15 and 14. During the suction stroke of the piston of the cylinder 3 the valves 54 place said cylinder 3 in communication with the intake chamber 12 to permit fuel to pass into said cylinder 3 by way of the fuel compression chamber 26 and passages 29 and 34. During the suction stroke of the piston of the cylinder 4 the valve 57 places said cylinder 4 in communication with the intake chamber 13 to admit air to said cylinder 4 by way of the air compression chamber 31 and passages 33 and 35. During the compression stroke of the pistons of the cylinders 3 and 4 the valves 57 and 54 close 20 and prevent the cylinders from having communication with the intake and exhaust chambers 12, 13, 14 and 15 so that during the compression stroke of the pistons the fuel will be compressed in the cylinder 3 and compression chambers 27, 25 26 and 28 and the air will be compressed in the air compression chambers 32, 30 and 31. During the compression of the air and fuel as described, the air and fuel will be kept separated from one another. During the compression strokes of the pistons the valves 48 and 51 close to prevent direct communication between the cylinders and the compression chambers. During the exhaust strokes of the pistons, the cylinders are placed in direct communication with the exhaust chambers 35 14 and 15 by the valves 48, 51, 54 and 57. The valves 54 and 57 are similarly constructed and in Figure 7 is shown the position occupied by the valves during the suction stroke of one of the pistons. It is to be understood that the valves 40 of one cylinder are similarly constructed to the valves of the other cylinder so that the showing made in Figure 7 applies to either one of the cylinders and it is to be noted that a direct communication is made between the intake passage 45 and the cylinder in Figure 7. Figure 10 shows the position of the valve in one of the cylinders as the piston thereof is on its compression stroke, the intake and exhaust passages being closed to the cylinder while the latter is in communication with the compression chambers due to the arrangement of passages between said compression chambers. In Figure 8 the valves are shown occupying 50 positions during the working stroke of the piston wherein the intake and exhaust passages are closed to the cylinder and the latter is in communication with the compression chambers so that the expanding gases may act on the piston. Figure 9 discloses the position of the valves during the exhaust stroke of the piston. It is to be 55 noted that the exhaust passages are in direct communication with said cylinders so that the latter may be freed of spent gases.

In operation, during the suction stroke of the pistons 5 and 6 fuel is drawn from the carburetor 65 into the cylinder 3 and air from the atmosphere is drawn into the cylinder 4. The fuel enters the cylinder 3 from the carburetor by way of the intake manifold 16, intake chamber 12, compression chamber 26 and passages 29 and 34. During the suction stroke of the piston 6 air is drawn from the atmosphere into the cylinder 4 by way of the manifold 23, intake chamber 13, compression chamber 31, passages 33 and 35. Thus during the suction stroke of the pistons 5 and 75

and 6, the cylinder 3 is supplied with fuel and the cylinder 4 is supplied with air, the air and fuel being kept separate, the fuel consisting of any type of fuel supplied to the carbureter and purified exhaust gases obtained from the cylinders in the previous cycle of operation of the engine. When the pistons 5 and 6 complete the suction strokes, the intake chambers 12 and 13 are closed to the cylinders so that the air and 10 fuel will be separately compressed in the cylinders and the associated compression chambers raising the compression ratio to a maximum. The valves 51 and 48 place the compression chambers in communication with each other and 15 with the cylinders when the pistons 5 and 6 complete the compression stroke, allowing the highly compressed air and fuel to meet and thereby bring about spontaneous combustion whereby the expanding gases may act on the 20 pistons to drive them on their working stroke. The pistons completing their working strokes, the valves occupy positions to permit direct communication between the cylinders and the exhaust chambers 14 and 15, allowing the pistons 25 tons to drive the spent gases into and through the gas purifier and to the gas cooler, the undesirable gases being separated from the desirable gases by the purifier, the undesirable gases escaping to the atmosphere while the desirable 30 gases pass to the cooler to be taken therefrom by the suction in the carbureter.

An engine of the character described works upon the four cycle principle and eliminates the use of electrical ignition also injectors found in 35 the Diesel type of engine. In an engine of the character described it is possible to materially increase the compression ratio without danger of pre-ignition. During the compressing of the air and fuel separately as heretofore described, both 40 will be raised to a high temperature so that when allowed to commingle spontaneous combustion will immediately take place. The purified exhaust gases mixing with the fuel and when compressed in the cylinder 3 will not explode due to 45 the lack of oxygen. However, when the highly compressed air is introduced therewith containing the oxygen the spontaneous combustion will immediately occur and thoroughly ignite all of the gases.

50 Having described the invention, I claim:

1. An internal combustion engine of the four cycle type comprising a cylinder block having cylinders, a head closing the cylinders, pistons operating in the cylinders, a crank shaft having

a crank connected to the pistons whereby said pistons move together, said head having fuel and air intake chambers and exhaust chambers, a fuel carbureter connected to the fuel intake chamber, an exhaust purifying and cooling apparatus connected to said exhaust chambers and to the carbureter, means for controlling and delivering fuel from said fuel intake chamber to one of the cylinders during the suction stroke of the piston thereof, a second means for controlling and delivering air from the air intake chamber to the other cylinder during the suction stroke of the piston thereof, said first and second means operating to close the cylinders to their respective intake chambers during the compression and 10 working strokes of the pistons, a third means for commingling the compressed air and fuel on the pistons reaching their working strokes to bring about ignition of the fuel to drive the pistons, said first, second and third means coacting during the exhaust strokes of the pistons to connect said cylinders to said exhaust chambers, and drive means for operating said first, second and third means from the crank shaft.

2. An internal combustion engine of the four cycle type comprising a cylinder block having cylinders, a head closing the cylinders, pistons operating in the cylinders, a crank shaft having a crank connected to the pistons whereby said pistons move together, said head having fuel and air intake chambers and exhaust chambers, a fuel carbureter connected to said fuel intake chamber, an exhaust purifying and cooling apparatus connected to said exhaust chambers and to the carbureter, said head having a group of 30 connected passages connecting one of the cylinders to said fuel intake chamber and a second group of connected passages connecting the other cylinder to the air intake chamber, said head having ports to connect said groups of passages 35 to each other and to the cylinders and to the exhaust chambers, first, second and third groups of valves carried by the head for controlling the passages and ports, said first group of valves acting to open and close one cylinder to said fuel 40 intake chamber and the other cylinder to the air intake chamber, said second group of valves acting to open and close the passages and cylinders to each other, said third group of valves coacting with the first and second group of valves to open 45 and close said cylinders with the exhaust chambers, and an operating means for the valves and driven by said crank shaft.

RICARDO D. CAYABYAB.
